[57] CLAIM

The ornamental design for a high-pressure rotary nozzle, as shown.

DESCRIPTION

FIG. 1 is a perspective view for a high-pressure rotary nozzle showing my new design therefor;
FIG. 2 is a side-elevational view thereof;
FIG. 3 is a front-elevational view thereof; and
FIG. 4 is a rear-elevational view thereof.

FIG. 1

FIG. 2

FIG. 3

FIG. 4
